[57] CLAIM

The ornamental design for a paint can rim cover with brush wiping wire, as shown and described.

DESCRIPTION

FIG. 1 is a top, front and side perspective view of a paint can rim cover with brush wiping wire showing my new design; FIG. 2 is a perspective view from the bottom;

FIG. 3 is a left side elevational view, the right side being a mirror image thereof;

FIG. 4 is a front elevational view;

FIG. 5 is a rear elevational view;

FIG. 6 is a bottom plan view; and,

FIG. 7 is a top plan view.

The broken line showing of a container is for illustrative purposes only and forms no part of the claimed design.
